UNITED STATES PATENT OFFICE

144,946

DESIGN FOR A FLASHLIGHT

Lester E. Stegman, Cincinnati, Ohio, assignor to Dayton Acme Co., Cincinnati, Ohio, a corporation of Ohio

Application June 30, 1945, Serial No. 120,434

Term of patent 14 years

(Cl. D48—24)

To all whom it may concern:

Be it known that I, Lester E. Stegman, a citizen of the United States, residing at Cincinnati, in the county of Hamilton and State of Ohio, have invented a new, original, and ornamental Design for a Flashlight, of which the following is a specification, reference being had to the accompanying drawings, forming part thereof, in which:

Fig. 1 is a perspective view of the flashlight, showing my new design.

Fig. 2 is an end elevational view of the same.

Fig. 3 is a side elevational view of the same.

Fig. 4 is a bottom view of the same.

I claim:

The ornamental design for a flashlight, substantially as shown.

LESTER E. STEGMAN.
